UNITED STATES PATENT OFFICE.

TITUS K. SMITH, OF BROOKLYN, NEW YORK.

WALL.

964,942.

Specification of Letters Patent. Patented July 19, 1910.

Application filed March 17, 1908. Serial No. 421,621.

To all whom it may concern:

Be it known that I, TITUS K. SMITH, citizen of the United States, and resident of Brooklyn, in the county of Kings and State 5 of New York, have invented certain new and useful Improvements in Walls, of which the following is a specification.

My invention relates to buildings and the object of same is to provide a building having a concrete wall or walls, in which are inclosed a plurality of hollow forms having spaces between them in which the concrete 10 is located.

A further object is to use said walls as a heater, and to this end the said forms are provided with a plurality of openings which register with the adjacent forms in such a way as to form flues which extend through the wall from the bottom upward to an out- 15

let provided to release the gases.

A further object is to provide means for heating said walls in a cheap and efficient manner evenly over the surface of the wall.

A further object is to provide a building 20 which may be quickly and economically built and which will be practically fireproof by reason of the materials used.

Referring to the drawings which form a part of this specification,—Figure 1, is a view of the interior of a building, the two side walls of which are shown in section, and the rear wall having a part of the inner plastering removed to disclose the forms or blocks in longitudinal section, and their relative arrangement. Fig. 2, is a perspective view of one of the hollow blocks or forms. Fig. 3, is a perspective view of one of the base blocks. Fig. 4, is a view of a modified form of block, the length of each being determined by the height and design of the building to be constructed. Fig. 5, is a view 30 disclosing a section of my wall in which are embedded the forms which in this case are shown as having oval sides.

My object is to build, in outside molds of temporary construction, a concrete wall having inclosed therein the blocks or forms which may be made of sheet iron, wood or plastic material and of any desired form, 40 such as round, oval or rectangular, to create inter-wall spaces, the interior of said forms serving as conduits, and extending vertically or horizontally, depending on the manner in which the forms are assembled.

It will be observed that by the construction disclosed in Fig. 1, the air may circu-

late both vertically and horizontally through the blocks or forms. The forms may be built in a wall which is supported in steel frames as in the present steel frame buildings if desired. 60

A, indicates a building having walls A', the outer facing A² of which is composed of concrete which extends through from the outer wall to the inner wall between the forms B, B, B, etc., as indicated at B'. The inner facing wall may also consist of concrete, if preferred, or the concrete may extend from the outer facing and between the forms B, until it comes practically flush 70 with the faces of the forms as indicated at B², and the inner facing could be made of the usual plastering material, but in either case the forms are entirely inclosed by the plastic materials. 75

The forms, or blocks, as I shall herein-after call them, may be formed as shown in Fig. 4, in which they are shown as rectangular in cross section and extending upward in unbroken columns for a predetermined 80 distance. In low dwelling houses they might extend from the bottom to the top of the house unbroken, but in high buildings I prefer to insert at predetermined heights, a line of blocks extending horizontally between the ends of the vertical sections, so that further gases might be introduced at this point to heat or cool the wall, since the gases introduced at the bottom of the lowest tier of blocks would part with their heat by 85 radiation before reaching the top of the wall and unless further heated gases were introduced, the upper portion of the wall would be comparatively cool. 90

The block B is rectangular in form and is provided at its upper and lower ends with openings B³, the upper and lower openings being in respective alignment with each other. 95

In starting the building, a base wall D is 100 first laid, unless it is to be of steel construction, in which case the composite wall would be built on the steel, and on said wall D is laid a row of blocks C with their openings C' upward, and on the blocks C is built up 105 an inner wall of the blocks B arranged relative to blocks C and to each other so as to form intercommunicating passages E, E, E, etc., which unite all of the spaces or chambers within the blocks together. After this part 110 of the wall has been built up a sufficient distance, a board wall constituting a form is

erected on the outer side and inner side of the blocks to a sufficient height, and the concrete introduced between the said board wall and the blocks and within the spaces formed 5 between the blocks as illustrated at B', the distance at which the said board wall is placed from the faces of the blocks, determining the thickness of the concrete portion of the wall, as will be readily understood.

10 After the complete wall has been built to the desired height by thus successively building the blocks and concrete portions, the blocks C are used to form a top or cap for the wall, the openings C' being made to 15 register with the openings B', so that the gases may flow from the blocks B to the conduit C' formed by blocks C and thence to an outlet C' of which there may be as many as may be required, depending on the size 20 of the building.

In Fig. 5 of the drawings there is shown a modification of the construction. In this form I use short, open ended, tubular sections —F— preferably formed in an elongated shape. When constructing the wall I introduce the cover —F, 1—, which is placed on the top of the row of sections as set, and between the intervening superimposed row of sections, as shown in Fig. 5. These covers 25 —F, 1— being thus disposed, the two ends of each block have open communication with two of the blocks above. Further, the covers —F, 1— produce lateral intervening spaces between the blocks. When the soft concrete is now poured it fills the intervening 30 spaces and rests upon the covers —F, 1—. The bottoms of the blocks are open, but the concrete will not rise upward into the blocks. The construction shown is advantageous in 35 that it produces radiation of the rising column of air in all directions. Further, the 40 construction is very economical.

G indicates the flooring of the building and H the ceilings thereof, and I indicates 45 a beam, the ends of which are supported by being inserted in spaces formed between the blocks B before the concrete filling is applied.

J indicates a heater which may be of the 50 hot air type, but I prefer to use steam for heating and to run a steam pipe k through the conduits in the base blocks C, as indicated in Fig. 4, so that the heat therefrom will rise and be distributed evenly throughout the wall, or if the wall was used in connection with a cold storage house or refrigerator, the cooling pipes could be located in 55 said conduits and the heat absorbed from the walls, as will be readily understood.

60 The blocks C may be provided with a pipe portion L, where necessary in constructing the building through which heated air may be forced into the conduits or gases withdrawn by suitable means such as a blower or pump. When the wall is made with hol-

low blocks and it is not desired to ventilate the same, the blocks may be formed without any openings, such as B'.

By the construction thus described, I am able to provide a cheap, durable, fireproof wall for the purpose set forth, and to ventilate and heat the rooms which said walls inclose, or cool the same in an easy and practical manner.

Having thus described my invention, what 75 I claim as new and desire to secure by Letters Patent, is—

1. A wall comprising a plurality of blocks having chambers formed therein, and forming communicating passages throughout the 80 wall, said blocks being separated laterally to form intervening spaces; a series of base blocks communicating to form a continuous space around the base of the wall and in communication with the said blocks superimposed thereon; a series of top blocks to form a continuous space around the top of the wall in connection with the wall blocks directly beneath; a duct leading into the space formed by the base series; a duct leading 85 from the space formed by the top series; and solid concrete filling said intervening spaces between the said blocks and forming the inner and outer faces of the said wall.

2. A wall comprising a system of hollow 90 tubes separated to form intervening spaces, and extended from the bottom to the top of the wall; a horizontal tube arranged to form an annular base connection between said tubes, a horizontal tube arranged to form 95 an annular top connection between said tubes; said base and top tubes provided with an inlet opening and outlet opening, respectively; and a hardened plaster material filling said intervening spaces, and 100 forming the face of the wall.

3. A wall comprising a plurality of short, tubular blocks arranged in courses with the hollow spaces vertical; tile-like spacing members covering the middle section of the 110 top of each block and spacing the superimposed blocks, so as to produce laterally intervening spaces between the said blocks; and a plastic, solid setting material forming the two faces of the wall, said plastic material filling said intervening spaces, and 115 keying the blocks in position.

4. A wall comprising a plurality of duplicate hollow blocks arranged in broken joint order with each upper block resting on two 120 lower to bridge between the same, each block having a top and bottom both provided with openings disposed to each side of the center and each opening engaging the opening of a superimposed block, said openings being 125 sufficiently removed to form laterally intervening spaces between the superimposed blocks when the ends of such blocks are rested on the ends of two lower blocks; and a plastic, solid setting material filling said in- 130

tervening spaces, and forming the faces of the wall.

5. A composite wall comprising a plurality of molded hollow blocks longitudinally disposed and spaced apart from each other to form openings between them, and a plurality of similar blocks in contact therewith located above and below said first named blocks and spanning said openings, thereby 10 forming recesses alternating with said blocks, and hardened plastic material located in and filling said recesses.

6. A composite wall comprising a plurality of hollow blocks longitudinally disposed and spaced apart from each other to form openings between them, each of said blocks having a plurality of passages therein, and a plurality of similar blocks located above and below said first named blocks and spanning said openings, thereby forming recesses alternating with said blocks, the passages in one block registering with those in one of the adjacent blocks to form a communicating conduit, and hardened plastic 25 material located in and filling said recesses to form an integral wall.

7. A composite wall comprising a plurality of molded blocks having chambers formed therein longitudinally disposed and spaced apart from each other to form openings between them, and a plurality of similar blocks in contact therewith located above and below said first named blocks and spanning said openings, thereby forming recesses alternating with said blocks, and blocks of hardened plastic material located in and filling said recesses; and plastic material also forming a facing for the wall.

8. A composite wall comprising a plurality of blocks having chambers formed therein, and longitudinally disposed and spaced apart from each other to form openings between them, each of said blocks having a plurality of passages therein, and a plurality of similar blocks located above and below said first named blocks and spanning said openings, thereby forming recesses alternating with said blocks, the passages in one block registering with those in one of the adjacent blocks to form a communicating conduit, and blocks of hardened plastic material located in and filling said recesses to form an integral wall; and a facing for said wall.

55. 9. A composite wall comprising a plurality of molded blocks longitudinally disposed and each having a plurality of passages in each of its top and bottom sides, a plurality of similar blocks located above

and below said first named blocks and having its passages registering with the passages in the first named blocks, cement means for binding said blocks in fixed relation to each other, and means for leading a fluid into the lower blocks and releasing 65 same through the upper blocks for the purpose set forth.

10. A composite wall comprising a plurality of molded blocks longitudinally disposed and each having a plurality of passages in each of its top and bottom sides, a plurality of similar blocks located above and below said first named blocks and having its 70 passages registering with the passages in the first named blocks, cement means for binding said blocks in fixed relation to each other, and means for leading a fluid into the lower blocks and releasing same through the upper blocks for the purpose set forth, 75 said means comprising a molded conduit located below and above said blocks respectively and having passages registering with the passages in said blocks.

11. A composite wall comprising a plurality of molded hollow blocks longitudinally 85 disposed and spaced apart from each other forming openings, and a plurality of similar blocks located above and below said openings and spanning same to form a closed top and bottom and forming between 90 said blocks, rectangular shaped openings, and blocks of hardened plastic material filling said openings, thereby forming a wall composed of blocks of solid hardened plastic material and blocks of hollow molded material 95 alternately disposed.

12. A composite wall comprising a plurality of molded hollow blocks longitudinally disposed and spaced apart from each other forming openings, and a plurality of similar 100 blocks located above and below said openings and forming between said blocks, rectangular shaped openings, and blocks of hardened plastic material filling said openings, thereby forming a wall composed of 105 blocks of solid hardened plastic material and blocks of hollow molded material alternately disposed, said molded blocks having passages in their upper and lower ends which connect said chambers together.

Signed at New York in the county of New York and State of New York this tenth day of March A. D. 1908.
